CLAIM

The ornamental design for a faucet handle, as shown and described.

DESCRIPTION

FIG. 1 is a perspective view of a faucet handle of the present design;

FIG. 2 is a front elevational view thereof;

FIG. 3 is a rear elevational view thereof;

FIG. 4 is a left side elevational view thereof, the right side being a mirror image; and,

FIG. 5 is a top view thereof.

The bottom of the faucet handle of the present design is not visible during normal use, such that the bottom view is omitted.

1 Claim, 5 Drawing Sheets(56)
